COIN SORTING MACHINE

Edward P. Donnellan, Brooklyn, N. Y., assignor
to Standard-Johnson Company, Inc., Brooklyn,
N. Y., a corporation of New York

Original application June 28, 1933, Serial No.
678,018. Divided and this application November
22, 1935, Serial No. 51,058

5 Claims. (Cl. 133—3)

This invention relates to improvements in machines for assorting and counting coins of mixed denominations; and the invention has reference, more particularly, to improvements in that type of coin counting machine disclosed in my prior Letters Patent No. 1,655,412, dated January 10th, 1928; this application being a division of my pending application for United States Letters Patent Ser. No. 678,018, filed June 28th, 1933.

5 This invention has for its principal object to provide a coin assorting and counting machine of the kind mentioned having an improved form and construction of rotatable coin carrier adapted to propel individual coins in operating engagement with counting mechanism, said carrier being so constructed as to provide, without substantial increase in diameter, a greatly enlarged coin carrying capacity, whereby a considerably larger number of coins can be handled thereby 10 without necessity for any substantial increase of peripheral speed, so that in effect a faster machine results, i. e. a machine capable of handling and discharging as counted a greatly increased number of coins in a given time period.

15 20 25 An illustrative embodiment of the present invention is shown in the accompanying drawings, in which:—

Fig. 1 is a top plan view of a coin counting machine according to this invention, with certain parts broken away to show underlying structure; Fig. 2 is a vertical section through the machine; Fig. 3 is a fragmentary plan view of a modified form of the coin distributor or feed mechanism of the machine; and Fig. 4 is a fragmentary side elevation of the rotary coin carrier.

Similar characters of reference are employed in the above described views, to indicate corresponding parts.

In the embodiment of my invention, as illustrated in the said drawings, the reference character 10 indicates a suitable supporting frame-work or housing. Suitably supported in connection with the frame-work or housing is a cylindrical bowl 11, open at its upper end but having a bottom wall 12 in which is formed a centrally located bearing portion 13. The bowl 11 is supported in an angularly disposed position, so that it slopes, preferably at an angle of approximately forty-five degrees from horizontal plane. Suitably secured to and extending over the upper open end of said bowl 11 is an annular hopper frame 14, which is preferably connected at its upper side to said bowl 11 by hinge connections 15, so that the same may be lifted up to uncover and give access to the mechanism mounted with-

5 10 15 20 25 30 35 40 45 50 55 60 65 70 75 80 85 90 95

in said bowl 11. Affixed to and across the lower end of said hopper frame 14 is a bottom plate 16, adapted, when the hopper is closed, to extend across the upper open end of the bowl, contiguous to the upper end of a rotary coin carrier 5 contained within the latter and which will be subsequently described. Connected with said bottom plate 16 is a central bearing portion 17 which is aligned with the bearing portion 13 at the bowl bottom.

10 Journaled in the bearing portion 13 is a rotatable spindle 18. Mounted in and across the frame-work or housing 10 is a transverse driven shaft 19 upon which is fixed a worm member 20 adapted to mesh with a worm gear 21 that is 15 affixed to the lower exteriorly projecting end of said spindle 18. Arranged within said hopper frame 14 to lie above and contiguous to said bottom plate 16 is a rotatable coin distributor or feed disc 22 having a hub portion 23 journaled 20 in said bearing portion 17. Affixed to said hub portion 23 is a spindle section 24 provided at its lower end with a male clutch or coupling member 25 which, when the hopper frame is in normal closed relation to the bowl, separably engages a female clutch or coupling member 26 connected with and rotated by said spindle 18, whereby rotative movement is transmitted to said distributor or feed disc 22. Said distributor or feed disc is of a thickness approximating the 25 thickness of the larger denominations of coins. The outer or side walls of the hopper frame surround the periphery of said distributor or feed disc. The distributor or feed disc is provided around its circumferential marginal portions with an outer annular row of coin receiving openings or pockets 27 and an inner annular row of coin receiving openings or pockets 28, those of one row being in staggered relation to those of the other row. At its lower side, the 30 hopper frame is provided with a segmental partition wall 14' spaced inwardly from the outer or side wall, and extending down to the distributor or feed disc so as to lie between said outer and inner rows of coin receiving openings 35 or pockets 27 and 28. The bottom plate 16, in one form, is provided in suitable locations, with coin delivery openings, one of said openings, as 29, lying in the path of movement and beneath the outer openings or pockets 27, and the other, as 30, lying in the path of movement and beneath the inner openings or pockets 28, whereby coins 35 conveyed upward in the hopper by the distributor or feed disc may drop from said respective openings or pockets through said respective delivery 40 45 50 55 60 65 70 75 80 85 90 95

openings for deposit in the coin carrier contained within the bowl 11, as will hereinafter more particularly appear. Suitable sheer plate means (not shown) is provided to remove excess coins so as to assure but a single coin at a time being conveyed in any given pocket, of the respective outer and inner rows 27 and 28 thereof, over and for delivery through the respective delivery openings 29 and 30.

10 Fixed on said spindle 18 so as to be rotated thereby within said bowl 11 and beneath said hopper bottom plate 16 is a coin carrier having a central hub-member 31 and a cylindrical body 32 which is connected with said hub-member 31 by spider arms 33. The cylindrical body 32 is provided around its outer circumference with a plurality of coin carrier members which are opposed to the annular wall of said bowl 11. These carrier members are arranged in two sets, 20 the carrier members 34 and the carrier members 35, the members of one set being alternated with those of the other set. Each carrier member 34 is provided with a substantially perpendicular coin receiving way, preferably in the form of a 25 radial slot 36 open throughout its length toward the annular wall of said bowl and closed at the back of the cylindrical body 32. In like manner, each carrier member 35 is provided with a similar perpendicular coin receiving way or slot 37.

30 The coin carrier members 34 and their ways 36 correspond in number to the number of coin receiving openings or pockets 27 in the outer annular row provided in the distributor or feed disc 22, and are respectively aligned therewith; 35 while the coin carrier members 35 and their ways 37 correspond in number to the number of coin receiving openings or pockets 28 in the inner annular row provided in the distributor or feed disc 22, the same being respectively aligned there- 40 with. Directly above and communicating with the ways or slots 36 of the coin carrier members 34 are funnel-like mouths 38 which respectively underlie the openings or pockets 27 of the distributor or feed disc, thus providing an outer 45 annular row of said funnel-like mouths cooperative with the outer annular row of feed-disc coin conveying openings or pockets. Inwardly off-set from but communicating with the ways or slots 37 of the coin carrier members 35 through inter- 50 connecting forwardly and downwardly inclined chute sections 39 are funnel-like mouths 40 which respectively underlie the openings or pockets 28 of the distributor or feed disc; thus providing an inner annular row of said funnel-like mouths 55 cooperative with the inner annular row of feed-disc coin conveying openings or pockets. Since the coin carrier and feed-disc rotate together, being each driven by the common spindle 18, the same are so related that as a coin conveying 60 opening or pocket 27 passes over the outer coin delivery opening 29 of the hopper bottom plate 16, a corresponding coin carrier member 34 passes beneath said delivery opening 29, and consequently a coin conveyed in the latter will drop 65 directly into the funnel-like mouth 38 of said passage carrier member so as to be deposited in the way or slot 36 of the latter; likewise, as a coin conveying opening or pocket 28 passes over the inner coin delivery opening 30 of the hopper bottom plate 16, a funnel-like mouth 40 of a corresponding coin carrier member 35 passes beneath said delivery opening 30, and consequently a coin conveyed in such opening or pocket 28 will drop directly into said funnel-like mouth 70 75 40, to thence pass downwardly and outwardly

through the communicating chute-section 39 into said passing carrier member 36 so as to be deposited in the way or slot 37 of the latter.

The annular wall of said bowl 11 is formed on its inner surface in opposition to the circumferential face of the coin carrier with a series of separate annular runways at different perpendicularly spaced levels, and respectively corresponding to the respective denominations or sizes of coins to be counted. As shown in the drawings, 10 the machine is arranged to handle three denominations of coins, viz. quarters, nickels, and dimes, so that three runways corresponding to each such denomination are provided, but it will of course be obvious that the machine may be 15 arranged to handle more or less denominations of coins by increasing or decreasing correspondingly the number of coin runways. As shown in the drawings, for the purpose of illustrating the principles involved in the coin runway arrangement, intermediate the top and bottom of the bowl 11 its annular wall is provided with an inwardly off-set annular shoulder 41 which forms a stop for the coin of largest diameter, in this illustration a quarter, and above this stop shoulder 41 the space between the bowl wall and the cylindrical body 32, forming the closed back of the ways of the coin carrier member, is slightly in excess of the diameter of a quarter and consequently provides a quarter-dollar runway. 20 Spaced below the stop shoulder 41 is the next inwardly offset annular shoulder 42 which forms a stop engageable by nickel coins, and thus limits a nickel coin runway beneath the quarter runway. In like manner, spaced below the stop- 25 shoulder 42 is another further inwardly offset annular shoulder 43 which forms a stop engageable by dime coins, and thus limits a dime coin runway beneath the nickel runway. From the above description it will be understood that a 30 coin of any denomination may be deposited in any of the ways or slots of either the carrier members 34 or 35, and when so deposited the same will gravitate to the particular runway corresponding to its size, the smaller coins passing 35 unobstructedly downward through the wider runways, while the larger coins are arrested by the stop shoulder limiting the bottom of the runways corresponding thereto. In this manner each coin entered in the coin carrier is at once 40 deposited or positioned in the path of travel dedicated solely to coins of its particular denomination, and consequently the coins are positioned in separated relation to move in separate paths 45 so as to be caused to actuate only the particular 50 counting mechanism corresponding thereto.

By providing the novel form and construction of carrier member having two sets of coin carrier members 34 and 35, the members of which are in alternated relation, with offset funnel 55 mouths and communicating chute sections serving one set, so that the respective sets are served from separate concentric annular rows of feed disc conveyer openings or pockets, I have, without necessity for enlarging the diameter of the 60 bowl 11, and without necessity for increasing the peripheral speed of the coin carrier and feed disc, substantially doubled the capacity of the machine, which in effect means that approximately twice the number of coins can be run 65 through the machine and discharged as counted within a given period of time. In fact, without enlarging the machine I am able to handle and count approximately 850 coins a minute as 70 against approximately 450 coins a minute which 75

was the capacity of the machine disclosed in my aforesaid earlier Patent No. 1,655,412. The advantages of this increase of capacity and resultant increase in speed of the ultimate count of 5 coins will be obvious.

The means for separately counting and registering the count of each particular denomination of coin comprises a set of counting registers of any well known type or style, comprising a 10 quarter primary register 44, a nickel primary register 45 and a dime primary register 46. Operative with each primary register (said primary registers being equipped with any well-known form of set-back means governable by the crank- 15 handle 47) is a cumulative register viz. the quarter cumulative register 48, the nickel cumulative register 49, and the dime cumulative register 50.

Suitably supported by brackets 51 affixed to the bowl 11, is a fulcrum post 52, pivotally connected with which are vertically spaced trip-levers, comprising a quarter actuatable trip-lever 53, a nickel actuatable trip-lever 54 and a dime actuatable trip-lever 55. The annular side wall of the bowl 11 is provided with slots 56 respectively communicating with the several coin runways, and through which the free ends of said trip-levers extend to lie in the path of movement of coins carried through said runways. The free ends of said respective trip-levers are provided 25 with nosings 57 engageable by coins past the trip-levers through the runways. The trip-levers 53, 54 and 55 are respectively provided with outwardly extending arms 53', 54' and 55' which carry upstanding studs 58. Also supported by 30 said bracket 51 is a fulcrum means 59 in connection with which are pivotally mounted a series of bell-crank levers 60, 61 and 62 corresponding respectively to the trip-levers 53, 54 and 55. One arm of each bell-crank lever is provided with a 35 bifurcate end portion 63 to straddle and thus operatively engage the studs 58 of the respective trip-levers. The bell-crank lever 60 is connected through a link 64 with the actuating lever 65 of the quarter register mechanism; the bell-crank lever 61 is in like manner connected through a link 66 with the actuating lever 67 of the nickel register mechanism, while the bell-crank lever 62 is connected through a link 68 with the actuating 40 lever 69 of the dime register mechanism.

Beyond the nosings of the trip levers, the sides of the bowl are cut away to provide a discharge opening 70 communicating with the several coin runways through which coins, after being counted are discharged from the bowl 11. Aligned to 45 serve the respective coin runways at said discharge opening 70 are discharge chutes 71, 72, 73; one of said chutes, as 71, receiving quarter coins; another, as 72, receiving nickel coins; and another, as 73, receiving dime coins. These 50 chutes respectively communicate with collector funnel means 74 beneath which collection receptacles may be placed, or to which coin receiving bags may be connected to receive counted batches of coins of predetermined number after 55 the same are counted.

As the coins are propelled through their respective runways by the coin carrier, the same, before reaching the discharge opening 70, are carried in passing engagement with the nosings 50 of the trip-levers, whereby the latter are turned on their fulcrums to transmit motion to the bell-crank levers, and through these by way of the links to the actuating lever of the respective register mechanisms, whereby each coin before 55 discharge, effects a registering impulse or unit

movement of the register mechanism assigned to count coins of its particular denomination.

The means for driving the feed disc 22 and coin carrier so as to deliver the coins in operative engagement with the coin register actuating devices, comprises a drive pulley 75 free to rotate on said shaft 19 but adapted to be normally clutched in driving relation thereto by any suitable form of releasable clutch mechanism (not shown). Said drive pulley 75 may be driven by belt 76, 10 or other suitable power transmission means, from any suitable power source, as e. g. an electric motor 77.

Referring to Fig. 3 of the drawings, I have shown an alternative arrangement of bottom 15 plate coin discharge means between the feed-disc 22 and coin carrier. In this arrangement, instead of providing the single coin delivery openings 29 and 30, each large enough to admit passage of coins of the largest as well as of smallest 20 diameter, I provide delivery openings having succeeding portions progressively graduated in size corresponding to the different diameters of coins 25 to be handled; these openings each including a dime section D, a nickel section N, and a quarter 30 section Q, and if other denominations of coins are to be counted additional sections corresponding thereto. These sections are so disposed that the smallest coin is deposited in a coin carrier 35 way or slot first and then a next larger coin, and so on. It will thus be obvious that the coins are assorted before deposit in the coin carrier, and furthermore, more than one coin can be carried in a single coin carrier way or slot provided they are of different denominations and provided they 40 are thus previously assorted so as to assure deposit of the smallest coin first followed by coins of increasing diameter. By this arrangement, the actual assorting of the coins precedes the deposit thereof in the coin carrier, and somewhat increased speed of counting can be attained, since more than one coin can be carried in the slots or 45 ways of the coin carrier.

I am aware that many changes could be made in the above described constructions and many 45 apparently widely different embodiments of this invention could be made without departing from the scope thereof as defined in the following claims. It is therefore intended that all matter contained in the above description or shown in 50 the accompanying drawings shall be interpreted as illustrative and not in a limiting sense.

I claim:—

1. In a machine of the kind described having a bowl provided with means to sustain coins of different denominations, for movement in correspondingly different annular paths, spaced in a common substantially vertical plane contiguous to a discharge opening with which the bowl is furnished, a coin carrier rotatable in said bowl, 60 said carrier having around its circumference a first and second set of radially disposed vertical carrying ways opposed to and open toward the sides of said bowl and adapted to hold the coins standing edgewise across their selective paths of 65 movement around the bowl, the members of said sets of ways being alternately arranged, said carrier having at its top an outer annular row of funnel-like mouths corresponding to and aligned directly over said first set of ways to lead downwardly thereinto, said carrier having at its top 70 an inner annular row of funnel-like mouths corresponding to and inwardly off-set from said second set of ways, said carrier having downwardly and outwardly inclined chute portions 75

extending between the latter mouths and the upper end portions of said second set of ways, the mouths of both rows thereof having downwardly inclined sides adapted to turn coins passing therethrough from flatwise positions to standing positions for operative disposition in said sets of ways, a hopper above said bowl and coin carrier, said hopper having a stationary bottom plate, a feed-disc rotatable in said hopper over said bottom plate synchronously with said coin carrier, said feed-disc having outer and inner annular rows of open conveyer pockets aligned over the respective outer and inner rows of the mouths of said carrier ways, said pockets corresponding in number and position to said mouths, and said bottom plate having coin delivery openings to afford communication between said feed-disc pockets and the mouths of said carrier ways as these parts move into registration therewith.

2. In a machine of the kind described having a coin distributing means as defined in claim 1 wherein the hopper is provided with a segmental partition wall spaced inwardly from the outer hopper wall to lie between the outer and inner rows of feed-disc conveyer pockets.

3. In a machine of the kind described having a circular bowl disposed about an inclined vertical axis, said bowl having means to sustain coins of different denominations for movement in correspondingly different paths to a discharge opening in the lower side of said bowl, a coin carrier rotatable in said bowl, said carrier having around its circumference a first and second set of radially disposed carrying ways opposed to and open toward the bowl sides, the members of said sets of ways being alternately arranged, said carrier having at its top outer and inner annular rows of funnel-like mouths, the mouths of one row being in staggered relation to those of the other row, the mouths of one row communicating with one set of ways and the mouths of the other row communicating with the other set of ways, and a feed disc rotatable with said coin

carrier, said feed disc having coin conveying pockets corresponding to the respective sets of coin carrier mouths, and a stationary plate intermediate said feed disc and coin carrier, said plate having coin passing openings therein.

4. In a machine of the kind described having a circular bowl disposed about an inclined vertical axis, said bowl having means to sustain coins of different denominations for movement in correspondingly different paths to a discharge opening in the lower side of said bowl, a coin carrier rotatable in said bowl, said carrier having around its circumference a first and second set of radially disposed carrying ways opposed to and open toward the bowl sides, the members of said sets of ways being alternately arranged, said carrier having at its top outer and inner annular rows of funnel-like mouths, the mouths of one row being in staggered relation to those of the other row, the mouths of one row communicating with one set of ways and the mouths of the other row communicating with the other set of ways, and means cooperative with the respective sets of mouths for delivering coins thereinto, a hopper above said bowl and coin carrier, said hopper having a stationary bottom plate, a feed-disc rotatable in said hopper over said bottom plate synchronously with said coin carrier, said feed-disc having outer and inner annular rows of open conveyer pockets aligned over the respective outer and inner rows of coin carrier mouths, and said bottom plate having coin delivery openings providing communication between said pockets and mouths.

5. In a machine of the kind described having a coin distributing means as defined in claim 4 wherein the hopper is provided with a segmental partition wall spaced inwardly from the lower portion of the outer hopper wall to lie between the outer and inner rows of feed-disc conveyer pockets.

EDWARD P. DONNELLAN.
